Term of patent 14 years

Int. Cl. D9—03

U.S. Cl. D9—193

FIG. 1 is a perspective view of a combined premium catalog and packaging container, showing my new design;

FIG. 2 is a sectional view thereof taken on the line 2—2 of FIG. 1;

FIG. 3 is a top plan view thereof;

FIG. 4 is a bottom plan view thereof;

FIG. 5 is a perspective view similar to FIG. 1 but showing a modified form of my new design;

FIG. 6 is a sectional view thereof taken on the line 6—6 of FIG. 5;

FIG. 7 is a top plan view thereof; and

FIG. 8 is a bottom plan view thereof.

I claim:

The ornamental design for a combined premium catalog and packaging container, substantially as shown and described.
